US0D1072976S

(12) **United States Design Patent** (10) **Patent No.:** **US D1,072,976 S**
(45) **Date of Patent:** **** Apr. 29, 2025**

(54) **EXERCISE MACHINE**

(71) Applicant: **YANGZHOU JIUYI HARDWARE & MACHINERY CO., LTD.**, Jiangsu (CN)

(72) Inventor: **Yen-Shuo Yang**, Taichung (TW)

(73) Assignee: **Yangzhou Jiuyi Hardware & Machinery Co., Ltd.**, Jiangsu (CN)

(**) Term: **15 Years**

(21) Appl. No.: **29/857,401**

(22) Filed: **Oct. 21, 2022**

(51) **LOC (15) Cl.** **21-02**

(52) **U.S. Cl.**

USPC **D21/673**

CLAIM

The ornamental design for an exercise machine as shown and described.

DESCRIPTION

FIG. 1 is a perspective view of an exercise machine showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dashed broken lines in FIG. 7 depict portions of the exercise machine that form no part of the claimed design.

1 Claim, 7 Drawing Sheets
